ARTISTIC PRICE TAG CORP., OF NEW YORK, N. Y., A CORPORATION OF NEW YORK

PRICE CARD

Application filed April 8, 1931. Serial No. 528,688.

This invention relates to a price card which may be used advantageously in conjunction with goods, wares and merchandise to advertise or indicate the price of the same.

5 The invention has for its general object, the provision of a device of the indicated character embodying improvements in construction enabling a display of a wide range of prices or quotations in conjunction with a comparatively small number of cards in that the parts thereof furnished to indicate the prices or quotations may be changed at will and be easily and conveniently attached and detached from a card whenever the occasions 10 arise.

The nature of the invention and its distinguishing features and advantages will appear when the following specification is read in connection with the accompanying drawings, in which

20 Figure 1 is a front view of a price card embodying the features of the invention;

Figure 2 is a section on the line 2—2 of Figure 1;

25 Figure 3 is a view of one of the characters or symbols used;

Figure 4 is a front view of a modified form of price card.

Referring now more particularly to Figures 1, 2 and 3, it will be apparent that the article of the present invention includes a plaque, card or plate 10 which may be of any suitable design or shape, and the same is made of thin sheet material such as metal or 30 celluloid, and in the present instance is made of celluloid. The card or plate has upstruck therefrom within the marginal edges thereof tangs or clips 11. The number and arrangement of tangs or clips 11 will depend 35 upon the nature and number of characters, symbols or numerals used in any particular case. In the present instance the number and arrangement of tangs or clips 11 suffice to accommodate three characters or numerals 40 designated 12. Each character or numeral 12 has notches 13 in the opposite end edges thereof. Each notch 13 opens through the opposite side faces of the character or numeral 12. The notches 13 will correspond to 45 the number and arrangement of tangs or clips

11. Each of the characters or symbols 12 is made of sheet material such as metal or celluloid, and in the present instance is made of celluloid. Each of the characters or numerals 13 may be of a color contrasting with the color of the card or plate 10. It will be understood that the card or plate 10 and also the characters or numerals 12 will be flexible by reason of the character of the material of which they are made. It will be apparent that the tangs or clips 11 may be readily engaged in the notches 13 of the characters or numerals 12, and by reason of the formation of the clips and notches, the clips will lie in part in the notches and extend in part over 55 the outside faces of the characters or numerals 12 to detachably secure the latter in place on the card or plate 10. It will be obvious that the characters or numerals 12 may be changed at will, and be easily and 60 conveniently attached or detached from the card or plate whenever the occasion arises. In this way a wide range of prices or quotations in conjunction with a comparatively 65 small number of cards or plates 10 may be 70 used thereby effecting an economy.

If desired, the body of the card or plate 10 may be formed with a recess 14 of any preferred size or shape to accommodate a supplementary display card 15 containing any 75 desired information such as the quantity of items which are sold for the price indicated by the numerals 12. The card 15 is held in place by tangs or clips 16 upstruck from the body of the card or plate 10. Provision is 80 also made for readily removing the supplemental card 15 from the recess 14 and consists of a small recess or depression 17 in the body of the card or plate 10. The recess or 85 depression 17 accommodates a person's finger or a suitable implement which may engage the card 15 to remove it.

The card or plate 10 is provided with suitable means for securing the same to goods, wares and merchandise in a displaying position. In Figures 1 and 2 this securing means is in the form of a two-prong clip 18, there being one at each side of the card or plate 10. If desired, the securing means may be in the 95 form of prongs or pins 19 secured to the card 100

or plate 10, as shown in Figure 4. In other respects, the article shown in Figure 4 is similar to that hereinabove described, and corresponding parts will be designated by 5 similar reference numerals.

Claims:

1. A device of the class described comprising a main part constructed of sheet material to provide a front flat surface and having 10 tangs formed from the material of said part and raised in relation to said surface, and separate characters constructed of flexible sheet material and each having notches in its edges which open through the opposite side 15 faces thereof to receive said tangs which extend in part within the notches and in part over the outside faces of the characters to thus detachably secure said characters in positions of display on said main part against 20 said front surface.
2. A device of the class described comprising a main part having an arrangement of clips, and separate characters of flexible material each having notches in the edges which 25 open through the opposite side faces thereof, the notches receiving the clips respectively in such manner that the clips extend in part in the notches and in part over the outside faces of the characters, to thus detachably 30 secure said characters in positions of display on said main part.
3. A device of the class described comprising a main part having an arrangement of clips, and separate characters of flexible material each having notches in opposite end 35 edges which open through the opposite side faces thereof, the notches receiving the clips respectively in such manner that the clips extend in part in the notches and in part over 40 the outside faces of the characters, to thus detachably secure said characters in positions of display on said main part.

Signed at 14 W. 37th St., in the county of New York and State of New York, this 6th 45 day of April, 1931.

JOSEPH FELDMAN.
SAMUEL J. MITTELMAN.
